UNITED STATES PATENT OFFICE.

CHARLES S. STAFFORD, OF SAN FRANCISCO, CALIFORNIA.

BORING-DRILL.

SPECIFICATION forming part of Letters Patent No. 645,219, dated March 13, 1900.

Application filed July 1, 1899. Serial No. 722,553. (No model.)

To all whom it may concern:

Be it known that I, CHARLES S. STAFFORD, a citizen of the United States, residing in the city and county of San Francisco, State of California, have invented an Improvement in Boring-Drills; and I hereby declare the following to be a full, clear, and exact description of the same.

My invention relates to boring and drilling devices.

It consists in the parts and the constructions and combinations of parts hereinafter described and claimed.

Figure 1 is a view of the drill. Fig. 2 is a vertical section of the same. Fig. 3 is a horizontal section on line $y-y$ of Fig. 2. Fig. 4 is a bottom view of the upper pinion. Fig. 5 is a view of the upper part of the sleeve. Fig. 6 is a vertical section of the same at right angles to Fig. 2. Fig. 7 is a bottom view of the sleeve. Fig. 8 is a top view of the lower pinion.

A is a stock which may be made of any suitable form. I have here shown it with the upper end made cylindrical or tubular in shape, having a breast-piece B and a supporting-handle C, by which it can be held with one hand while the other operates the crank D, which is fixed so as to turn the beveled driving-gear 30 E. This gear-wheel has the exterior toothed part E' and the inner toothed portion E².

The spindle F is screw-threaded and is supported and turnable in the stock A, its upper end extended into the tubular upper portion 35 when it is retracted and having sufficient length to allow it to be advanced as much as may be desired. Upon this spindle is loosely mounted the sleeve F', having a longitudinal slit on one side, and its central portion is 40 threaded on the outside, as shown. Upon the ends of this sleeve are mounted two beveled pinions G and G', the outer one engaging the outer teeth E' of the bevel-wheel and the inner one engaging the inner teeth E². These pinions 45 are loosely turnable upon the sleeve, and between them is mounted a longitudinally-slid-able two-part collar H, having in the interior a feather I, which, passing through the slit in the sleeve, engages with a keyway f in the 50 spindle, so that the two-part collar and the sleeve are always turnable with the spindle.

The pinions G G' have upon them projecting toward the collar lugs i, and the collar has corresponding grooves or sockets formed in its ends, so that when the collar is advanced 55 in one direction it will engage the lug i upon one of the pinions and be disengaged from the other, and when advanced in the opposite direction it will in the same manner be disengaged from the first pinion and engaged with 60 the other. By this movement of the collar the speed of rotation of the drill may be changed and will depend upon whether the interior or exterior gear is doing the driving.

When boring with a small boring-tool, the 65 exterior gear may be made to drive and produce a higher rate of speed; but if a larger boring-tool is being used the interior gear may be made to do the driving, and the rate of rotation will be slower.

In order to move the two-part collar H along the sleeve, a milled disk J is interposed between the two parts of the collar, and the inner portion is threaded, so that it turns upon the threaded portion of the sleeve. The two 75 parts of the collar are united to move in unison by turning up or forming lugs upon the end of the feather I, which thus engage with the two parts of the collar and hold it so that it moves practically as one piece. It will be 80 seen that by turning the disk J in one direction it will be advanced along the sleeve, so that when the lug i of the disengaged pinion is in line with the corresponding slot h in the adjacent end of the collar the latter may be 85 moved so that its slot will engage with the lug of that pinion, while at the same time the slot at the opposite end of the collar will be disengaged therefrom, thus changing the driving from one gear to the other.

To the lower end of the spindle is fixed the 90 chuck K, of any suitable or desired character, which will hold the boring tool or drill in line with the spindle.

L is a sleeve which forms the lower part of 95 the stock A, and within this sleeve is loosely fitted an interiorly-threaded collar O. The inner end of this collar is grooved or channeled upon the outside, as shown at O', and a screw or pin P, passing through the sleeve, 100 engages with this groove, so that the collar may rotate without advancing. Within the

sleeve is fitted a segmental brake-piece Q, the inner face of which has the same curvature as the exterior of the collar, and by means of a screw R, having a milled head, this brake-piece may be forced against the collar, so as to lock it and prevent its turning. In this condition when the drill-spindle F is turned it will advance through the collar by means of the engaging screw-threads and will thus feed forward at a rate dependent upon the pitch of the screw-threads. When the brake-shoe Q is tightened against the collar O, the drill-spindle will feed, but only when the sleeve L is held against independent rotation. 15 If it is desired to stop the feed, the screw R is loosened and the pressure upon the brake-shoe Q relieved. This allows the collar to turn freely within the sleeve, being guided by the annular groove and pin previously described; but it does not advance the spindle, since its frictional pressure upon the screw is sufficient to cause it to turn with the screw and produce no advance or feed of the boring-tool. Whenever it is desired to feed again 25 by tightening the brake, the collar will be stopped, and the screw will then advance within it as much as may be desired.

The flange of the collar O has a raceway to receive balls, which travel against the flange 30 of the sleeve and reduce friction when there is no feed, thus allowing the collar to turn easily. By a set-screw r the collar may be fixed to the spindle when no feed is desired.

In order to hold the work against the pressure of the boring-tool, the yoke S is fitted and loosely turnable upon the sleeve L, and the projecting ends of the yoke are fitted in any suitable or desired manner to receive a flexible chain T, one end of which being connected 35 with one end of the yoke the bight of the chain is passed around the part to be bored or drilled and the other end is connected with the opposite side of the yoke, thus holding the work, so that when the drill is advanced 45 it does not push the work away.

Having thus described my invention, what I claim as new, and desire to secure by Letters Patent, is—

1. In a boring-tool, a stock, a screw-threaded 50 spindle loosely turnable within the stock, with means for securing the boring-tool in line therewith, a sleeve loosely mounted on said spindle having a longitudinal slit and its central outer portion threaded, a beveled gear 55 journaled and turnable upon the side of the stock having outer and inner teeth, corresponding beveled pinions loosely turnable upon the ends of the sleeve, having lugs upon their adjacent faces, a two-part sliding collar 60 loosely fitting the sleeve between the pinions, having slots in its outer ends adapted to engage either of the lugs upon the pinions, a feather movable in a keyway in the spindle and means for advancing the two-part sliding collar in either direction to engage with

one of the pinions and disengage it from the other.

2. In a boring-tool, a stock, a threaded drill-spindle turnable therein, a sleeve loosely mounted on the spindle having a longitudinal slit and its central portion threaded, a gear-wheel journaled and turnable upon the stock having outer and inner rows of teeth, pinions loosely turnable upon the ends of the sleeve and engaging the outer and inner teeth 70 of the wheel, a two-part sliding collar interposed between the pinions having a length less than the distance between the pinions, a milled disk turnable with relation to the collar, having the interior screw-threaded and fitting corresponding threads upon the central part of the sleeve, lugs projecting from the adjacent faces of the pinions, corresponding slots in the outer ends of the two-part collar, so that one pinion will be engaged and the 75 other disengaged by the advance of the collar along the spindle.

3. In a boring-tool, a stock, a drill-spindle turnable therein, a sleeve mounted on the spindle, a driving-gear journaled and turnable upon the stock, and having outer and inner rows of teeth, pinions turnable upon the sleeve, the teeth of one engaging the outer and the other the inner teeth of the gear, a two-part collar loosely fitting the sleeve between the pinions having slots in the ends 95 adapted to engage corresponding lugs upon the inner faces of the pinions, a key or feather slideable in a keyway in the spindle having its ends upturned to engage the two parts of the 100 collar and unite them so that they become one and move in unison, a disk turnable upon the sleeve between the inner ends of the two-part collar having screw-threads fitting corresponding threads on the sleeve whereby the 105 collar may be advanced to engage either of the pinions and be disengaged from the other.

4. In a boring-tool, the combination of a stock, a drill-spindle turnable therein and mechanism by which it is rotated, a sleeve 110 forming the lower end of the stock and an internally-threaded collar loosely turnable within the sleeve, having its inner end formed with an exterior annular groove and its lower end provided with an antifriction-bearing for 115 the sleeve, a screw or pin passing through the inner end of the sleeve and engaging the annular groove in the collar, to prevent end movement of said collar, a brake-piece loosely seated in the sleeve and a screw for operating the same, a yoke loosely seated on the outer end of the sleeve below the said brake-screw and a means carried by the yoke for engaging the work to be drilled.

In witness whereof I have hereunto set my hand.

CHARLES S. STAFFORD.
